UNITED STATES PATENT OFFICE.

MARTIN NYSTROM, OF CHICAGO, ILLINOIS, ASSIGNOR TO THE BRUNSWICK-BALKE-COLLENDER COMPANY, OF WILMINGTON, DELAWARE, A CORPORATION OF DELAWARE.

STATION-SELECTOR DIAL FOR RADIO RECEIVING SETS.

Application filed July 25, 1925. Serial No. 46,044.

This invention relates to station selector dials for radio receiving sets and its object is to provide a dial of simple construction which can be easily manipulated to readily 5 secure fine adjustments for selecting different broadcasting stations, as desired.

In the accompanying drawings illustrating selected embodiments of the invention—

Fig. 1 is a plan view showing a pair of station selector dials with a portion of the instrument board of a radio receiving set.

Fig. 2 is an elevation of the parts shown in Fig. 1.

Fig. 3 is a sectional view on the line 3—3 15 of Fig. 1.

Figs. 4, 5 and 6 are detail views.

Referring to the drawings, 7 is the instrument board, 8 is the loop tuning condenser and 9 is the oscillator tuning condenser, each of these condensers having 20 rotor plates mounted on rock shafts 11. I have not attempted to show the detail construction of the condensers because they are familiar in the art and need no further description. Each condenser is supported on a frame 12 which is fastened to the inside of the instrument board 7. The shaft 11 carries a gear 13 which meshes with a gear 14 on a sleeve 15 which is rotatably mounted on a spindle 16 rigidly secured in the frame 12. The sleeve 15 has a flange 17 and a dial plate 18 is secured to the flange by one or more screws 19 or other suitable means. A dial 19 is clamped against the dial plate by a disk 35 20, which is screw-threaded on the upper end of the sleeve 15. An index plate 21 carrying a pointer 22 is rigidly secured in fixed position on the reduced end 23 of the spindle 16, the outer portion of this reduced 40 end being threaded to receive a clamping nut 24. The index plate has an aperture 25 with oppositely disposed extensions 26 to engage the spindle and a cross pin 27 carried by the spindle is arranged to engage the 45 extensions 26 of the aperture to hold the index plate in fixed position. The dial 19 is held in place on the dial plate 18 by a spring ring 28 of usual construction, which is sprung 50 into a groove 29 formed in the upstanding peripheral wall 30 of the dial plate. The outer surface of this wall is preferably knurled or serrated or roughened to facilitate the operation thereof.

In practice the parts being arranged in the

usual position, the dial plate 18 is manipulated by turning it back and forth as required to select a desired broadcasting station. The dial plate being fast to the sleeve, any movement of the dial plate is communicated to the rotor plates of the condenser 60 through the condenser shaft and gearing intermediate of the shaft and the dial plate sleeve. The two dial plates will be manipulated correspondingly to select a station in the usual manner, and this form of station 65 selector dials will be found adapted for sensitive operation so that the selection of stations will be greatly facilitated.

I am aware that changes in the form, proportion and arrangement of parts of the 70 selected embodiment of the invention illustrated in the drawings may be made without departing from the invention or sacrificing the advantages thereof, and I reserve the right to make all such changes as fairly fall 75 within the scope of the following claims.

I claim:

1. A station selector dial for a radio receiving set comprising a fixed spindle, a revolute sleeve on the spindle, a dial plate mounted on the sleeve to revolve therewith, and having a seat therein to accommodate the dial, a dial seated within the dial plate, and an index pointer rigid with the spindle and projecting over said dial.

2. A station selector dial for a radio receiving set comprising a fixed spindle, a revolute sleeve on the spindle, a flange on the sleeve, a dial plate fastened to the flange, a dial on the dial plate, a disk on the sleeve 90 clamping the dial against the dial plate, and a pointer rigid with the spindle and projecting over the dial.

3. A station selector dial for a radio receiving set comprising a fixed spindle, a revolute sleeve on the spindle, a dial plate mounted on the sleeve to revolve therewith, a peripheral wall on the dial plate and having a groove the outer surface of said wall being roughened, a dial on said plate, a ring 95 engaging said groove and clamping the edge of the dial against the dial plate, a disk on the sleeve clamping the central portion of the dial against the dial plate, and a pointer rigid with the spindle and projecting over 100 the dial.

MARTIN NYSTROM.
